[57] ABSTRACT

A swing-fit game comprising the assemblies of a male and a female three dimensional element which are respectively suspended from the hands of a user. The suspended members are manipulated such that the male member is made to swing into the female member.

SUSPENDED TARGET AND PROJECTILE

BACKGROUND OF THE INVENTION

The present invention relates to an amusement toy or game, requiring manipulative skill, knowledge of operation and the precision of the user. Such a device may be used to test both the coordination of the hands and the patience of the individual trying to achieve the object of the game. This type of game provides a great deal of amusement for children and, indeed, adults who use the same.

SUMMARY OF THE INVENTION

The device consists of a male and a female three dimensional element, each attached by a string to a different holder. When both elements are suspended from the hands of a user, the opening or openings located on the lateral faces or surfaces of the female element will form an angle with the vertical direction of the male element which will prevent the male to be inserted into any opening of the female element in either vertical or horizontal movements. The object of the invention is to put the said elements into a specific motion hence making the insertion possible.

BRIEF DESCRIPTION OF THE DRAWINGS

FIG. 1 is a side elevation of the preferred form of the male element assembly.

FIG. 2 is a side elevation of the preferred form of the female element assembly.

FIG. 3 is a top view of the male element assembly.

FIG. 4 is a top view of the female element assembly.

FIGS. 5, 6, 7, 8 are some alternate embodiment of the invention.

FIG. 9 illustrates how the insertion of the male element into the female's opening is prevented if the elements are moved either in a horizontal or vertical direction.

FIG. 10 illustrates the method of insertion when only the male element is pendulated.

FIG. 11 illustrates the method of insertion when only the female element is pendulated.

FIG. 12 illustrates the method of insertion when both the male and female elements are pendulated in opposite directions.

DESCRIPTION OF THE PREFERRED EMBODIMENTS

Referring to FIG. 2 the numeral 23 designates in its entirety the preferred embodiment of a female element assembly. The member 20 is a holding ring of suitable size to accomodate the holding of the female element or first member. Suspended from the ring 20 by means of a wire, cord or filament 21 is a female three dimensional element 22. In a preferred embodiment the female element 22 has the shape of a ring with a circular opening. The point of attachment of the wire or filament 21 to the said element is positioned at the outer periphery of the ring at a point corresponding to the center of gravity. In an alternate embodiment a part or the entire female element may be constructed from a heavier material such as cast steel to provide a more stable and hence easier to manipulate element. In FIG. 1 the numeral 27 indicates a preferred embodiment of a male element assembly. Member 24 is a holding ring with the same specifications as member 20 of the fe-

male element assembly illustrated in FIG. 2. The male element or second member 26 is attached to the holder 24 by means of a wire, cord, or filament 25. In a preferred embodiment the male element has a cylindrical form with a conical shaped tip to simplify the insertion, this member being longitudinal with greater length than diameter. The point of attachment of the wire or filament 25 is positioned at the flat end of the male element at a point corresponding to the center of gravity. This will enable the said element to remain erect and co-axial with its wire or filament. In an alternate embodiment a part or the entire male element may be constructed from a heavier material such as cast steel to provide better stability. The diameter of the male element is sufficiently smaller than the opening diameter of the female element 22 to simplify the insertion. Also in this embodiment the length of the male or second member is greater than the corresponding length of the first member's aperture.

The male element 26, female element 22 and the holding rings 20, 24 may be constructed of plastic, wood or metal materials. It will become obvious after reading the specifications that many variations in the geometric shape of the male element, female element and its opening or openings are possible without departing from the scope of this invention. For example the male element may be made in a spherical shape and the female element in the form of a cube with different shapes of openings on its four lateral faces. Some of the possible variations are illustrated in FIGS. 5, 6, 7, 8. It is also obvious that the size and shape of the male and female elements, as well as the shape, the size and location of the female's opening may be altered to make the task of insertion either easier or more difficult.

OPERATION

The swing-fit game consists of a male and a female three dimensional element, respectively suspended from the hands of a user. The preferred form of the invention is illustrated in FIGS. 1, 2, 3, 4. The object of the game is to fit the male element into the female's opening. In its geometric shape, the female element provides one or more non-horizontal openings on its faces or surfaces. When the elements are suspended, the said opening or openings will form an angle or angles with the male element hence preventing the insertion of the male into any opening of the female element in either vertical or horizontal movements. FIG. 9 illustrates the difficulty of insertion of the male element for the preferred embodiment of this invention.

In order to make the insertion possible, the position of the male in respect to the female must be changed to provide sufficient slanting between the male and the opening surface of the female element. The three following practical methods may be applied for the engagement of the preferred male and female elements as illustrated in FIGS. 10, 11, 12.

The female element is held steadily by one hand while the male element is pendulated in proper amplitude, direction and distance from it by the other hand of the user. In an instant when the male element is properly aligned with sufficient slanting in relation to the center of the female's opening as indicated in FIG. 10, the entire male assembly is to be descended for engagement with the female element.

The female element is to be pendulated in a proper amplitude and direction by one hand while the male el-

ement is held steadily in a suitable distance from it by the other hand of the user. The male element is to be descended where the two elements are properly aligned with a sufficient slanting as indicated in FIG. 11.

Both the male and female elements are to be pendulated in opposite directions in a suitable distance and proper amplitudes. The male element is to be descended for engagement with the female where the two elements are precisely aligned with sufficient slanting as indicated in FIG. 12.

The same procedures may be applied for other alternate forms of the invention where the female element may have more than one opening.

While this device is particularly suited for use by a single person, two or more persons may work in time competition to achieve desired results. In the alternate form where the female element may consist of more than one opening, the score for each opening may be considered upon the difficulty of the task of insertion related to the location and characteristic of the opening itself. The score for the male element may also be considered upon the difficulty of the task of insertion where more than one male element is being used with a single opening of a female element.

I claim:

1. A game comprising first and second members suspending from first and second spaced-apart suspension means, the first member, which when upright has top and bottom parts defining a first vertical axis, and at least one side face intermediate said top and bottom parts, the side face including therein an aperture of a predetermined vertical length and horizontal width, the game further comprising a flexible cord having one end secured to said top part of the first member for suspending said member to hang in said upright position, the cord having a remote end for engagement to said first suspension means, the cord when used remaining substantially axial with the vertical axis of said first member, the second member, which when upright, has

top and bottom parts defining a second vertical axis, and this member having an outer shape generally the same as said aperture but having length and width dimensions less than that of said aperture for permitting insertion of said second member through said aperture, the game further comprising a second flexible cord having one end secured to the top part of said second member for suspending said member to hang in said upright position, the second cord having a remote end for engagement to said second suspension means, the second cord when in use remaining substantially axial with the second vertical axis, said second member when vertical having a basic height equal to its axial length, at least one of said first and second members being swingable toward the other to reach an inclined position of the axes of the swung member and its cord, whereby the second member is insertable into said aperture while said first and second cords remain axial with respect to the axes of their respective members.

2. A game as defined in claim 1 wherein said first member is a ring and the second member is a rod.

3. A game as defined in claim 1 wherein said members have weight substantially greater than their respective cords for maintaining said cords in tension when suspended.

4. A game as defined in claim 1 wherein said first member is a hollow body and said aperture is in a wall of said body.

5. A game according to claim 4 wherein said first member is rectangular having four side walls, and said aperture is in one of said walls.

6. A game according to claim 1 wherein said first member is generally flat with a rectangular aperture therethrough.

7. A game according to claim 1 wherein said first member is circular, and said second member is conical having the pointed end thereof remote from the first end of the corresponding cord.
